UNITED STATES PATENT OFFICE.

EDWARD S. HALL, OF ROCHESTER, NEW YORK.

REGISTER.

1,108,902.

Specification of Letters Patent. Patented Sept. 1, 1914.

Application filed February 28, 1913. Serial No. 751,261.

To all whom it may concern:

Be it known that I, EDWARD S. HALL, of Rochester, in the county of Monroe and State of New York, have invented certain new and useful Improvements in Registers; 5 and I do hereby declare the following to be a full, clear, and exact description of the same, reference being had to the accompanying drawings, forming a part of this 10 specification, and to the reference-numerals marked thereon.

My present invention relates to registers or devices whereby indications may be produced, selectively, with reference to the 15 units of a series of names, characters or devices toward which it is sought to attract the attention, and it has for its object to provide a simple and efficient device of this 20 character that will be convenient in use and which may be produced in some of its forms at a very small cost.

A further object of the invention is the production of a device which, by reason of its cheapness and other characteristics, will be suitable for production as an advertising 25 novelty that can be distributed gratuitously or at a nominal price because of its inexpensive nature and the concurrent display of advertising matter that it is well adapted 30 to bear.

To these and other ends the invention consists in certain improvements and combinations of parts all as will be hereinafter described, the novel features being pointed 35 out in the claims at the end of the specification.

In the drawings: Figure 1 is a front elevation of a portion of a register constructed in accordance with and illustrating one embodiment of my invention, the portions 40 broken away being in the nature of structural repetitions, merely, of the portions shown; Fig. 2 is a transverse section taken substantially on the line 2—2 of Fig. 1, and 45 Fig. 3 is a view similar to Fig. 2 illustrating the mode of operation.

Similar reference numerals throughout the several figures indicate the same parts.

Although my invention is applicable in 50 a number of ways similar as to structure and general purpose, but embodied in products commercially different, I contemplate as an instance of its use, its embodiment in what is generally known as a "kitchen reminder" 55 and such an article is illustrated in the accompanying drawing. These reminders com-

prise a list of grocery supplies and other commodities of the kitchen or household usually arranged in alphabetical order and which the housewife runs over in formulating her orders, or marks in some manner, in the order in which they occur to her, the items that she must replenish in giving her next order.

In the practice of my invention, as embodied herein, I provide a stiff backing 1 of cardboard or other suitable material in which is formed one or more view openings 2 that are preferably long and narrow and run in a direction from top to bottom of the 60 backing. Spanning the openings in pairs are a plurality of resiliently flexible members 3 and 4, further description of which will be directed to a single pair inasmuch as the others are merely duplications. These 65 members 3 and 4 may be formed of bristol board or other high grade flexible paper materials that possess a fairly great amount of elasticity so that they will not become 70 "set" with reasonable usage and their attached ends are affixed to the rear of the 75 backing at points removed a greater or less degree from the margins of the opening 2 according to the length that must be allowed 80 freedom of movement for the production of 85 the requisite resiliency, while their free ends are arranged to overlap each other so that the fingers are superposed one upon the other.

The finger 3 is longer than the finger 4 90 or occupies a greater amount of the width of the opening in order that it may give room on its face for the inscription of a legend or character of the nature shown, whereby the said finger constitutes an index 95 member and I prefer to square off the end thereof as appears in the illustration. The finger 4 I prefer to provide with a tapered end portion 5 as shown, and so much of this end portion as is covered by the overlapping 100 end of the index 3, I prefer to color in a distinguishing manner so that there will be marked contrast, upon inspecting the members, when the finger 4 is superposed upon the index 3, rather than beneath it, so that 105 the member 4 constitutes an indicator calling attention to the corresponding index.

In operation, the fingers being normally 110 in such relative positions that the index fingers 3 overlap the ends of the indicators 4, when it is desired to register a given character, the index finger 3 is simply

pressed in or deflected as shown at the left of Fig. 3, to a sufficient extent to permit the coöperating yielding indicator 4 to snap past it whereupon a release of the pressure allows the index member to return but to a reversed position with reference to its indicator which latter will then be uppermost with its colored and pointed end 5 displayed to view adjacent to the inscription. To reset the register, the manipulation of the members is reversed, that is, the indicator 4 is pressed in causing the index member 3 to yield and reassume its normal position at the front.

15 Aside from the fact that the pointed conformation of the indicators 4 gives them a distinguishing characteristic when in the "on" position, it also reduces to a minimum the frictional contact with the coöperating member and the liability of the fingers to be caught edge to edge in deflected positions in such manner that neither may return to a straightened position.

In the present embodiment, I have shown 25 the indicator fingers 4 at the left formed integrally on a single sheet 6 the body portion of which is secured to the rear of the backing 1 and the index fingers 3 at the right similarly produced from a sheet 7, 30 while the intermediate sets, respectively, of both indicators and indexes are formed together from an integral sheet 8, this being an item of simplicity and economy in the manufacture of the device.

35 It will be understood that the backing 1 may be of such a size and form as will cause it to best lend itself to the reception of printing, illustrations or other advertising matter that it may be desired to display to 40 users of the device, but it is again stated that this invention is not necessarily limited to either "kitchen reminders" or to cheap paper constructions of the kind described. It is contemplated that celluloid, 45 ivory or thin spring metal are suitable as materials for use in the construction of the yielding fingers.

I claim as my invention:

1. A register comprising a pair of members supported at their far ends and arranged in superposed relationship to overlap each other at their adjacent ends, one constituting an index having the major part of its surface permanently exposed and the other a coöperating indicator, the on and off positions of the latter with respect to the index being alternately effected by reversing the superposed relationship of the members.

60 2. A register comprising a pair of members supported at their far ends and arranged in superposed relationship to partially overlap each other at their adjacent ends, one constituting an index having the 65 major portion of its surface permanently

exposed and bearing a legend and the other a coöperating indicator having its overlapping portion visually distinguished from that of the index, the on and off positions of the indicator with respect to the index being alternately effected by reversing the superposed relationship of the members.

3. A register comprising a pair of projecting members arranged in superposed relationship to overlap each other and constituting, respectively, an index and a coöperating indicator, one of said members being resiliently flexible to permit it to pass the other laterally whereby the on and off positions of the indicator with respect to the index may be alternately effected by reversing the superposed relationship of the members.

4. A register comprising a pair of flexibly resilient overlapping members, respectively, constituting an index and a coöperating indicator, the on and off positions of the latter with respect to the former being alternately effected through reversing the superposed relationship of the members by thrusting the uppermost member past the lowermost.

5. A register comprising a pair of resiliently flexible overlapping fingers, respectively, constituting an index bearing a legend and a coöperating indicator having its overlapping portion visually distinguished from that of the index, the on and off positions of the indicator with respect to the index being alternately effected by thrusting one finger past the other whereby the superposed relationship of the members is reversed.

6. A register comprising a pair of projecting members arranged to overlap each other and constituting, respectively, an index and a coöperating indicator, having its overlapping portion visually distinguished from that of the index by contrasting coloring, one of said members being resiliently flexible to permit it to pass the other whereby the on and off positions of the indicator with respect to the index may be alternately effected by reversing the superposed relationship of the members.

7. A register comprising a pair of projecting members arranged to overlap each other and constituting, respectively, an index and a coöperating indicator having its overlapping portion tapered, one of said members being resiliently flexible to permit it to pass the other whereby the on and off positions of the indicator with respect to the index may be alternately effected by reversing the superposed relationship of the members.

8. In a register, the combination with a backing board having an opening therein, of a plurality of flexible fingers secured thereto and projecting toward each other

in superposed pairs with their ends overlapping, the fingers of each pair constituting, respectively, an index and a coöperating indicator and the on and off positions of the latter with respect to the former being capable of being effected through reversing the superposed relationship of the mem-

bers by thrusting the uppermost member past the lowermost.
